UNITED STATES PATENT OFFICE.

HALE CHADWICK, OF PENACOOK, NEW HAMPSHIRE.

MACHINE FOR CLEANING AND SEPARATING CRANBERRIES.

SPECIFICATION forming part of Letters Patent No. 377,667, dated February 7, 1888.

Application filed January 6, 1887. Serial No. 223,605. (No model.)

To all whom it may concern:

Be it known that I, HALE CHADWICK, a citizen of the United States, residing at Penacook, in the county of Merrimac and State of New Hampshire, have invented a new and useful Machine for Cleaning and Separating Cranberries, of which the following is a specification.

The object of this invention is to provide a machine for cleaning and separating the dirt from cranberries, which may be driven by power or by hand; and the invention consists in the combination of the vibratory and stationary screen, a feed or carrying wheel, and various other mechanism, all of which will be hereinafter fully explained and pointed out in this specification and appended claims and be clearly illustrated in the accompanying drawings, forming an inseparable part thereof, of which—

Figure 1 is a vertical sectional elevation of the machine, Fig. 2 being a general plan view of same. Fig. 3 is a detached elevation of the drive-wheel, and Fig. 4 represents a portion 25 of the machine in side elevation.

Similar letters indicate corresponding parts.

A represents the frame supporting the inclined chute B, whose sides may be vertical and parallel one with the other, except at its 30 mouth, which may be contracted or narrowed some by the pieces b b, in order to check the discharge of the berries, for a purpose to be hereinafter described.

A frame-work, A', rising from the top of 35 the inclined chute B, supports a hopper, C, for receiving the berries, which fall thence into a vibratory screen, D, having flexible supports E at one end and a supporting-bar, d, either end of which rests in a slot formed in the vertical sides of the inclined chute B.

I would have it understood that I do not confine myself to any particular mechanism for agitating this screen D, as various devices may be used for this purpose, one simple means 45 being shown in the drawings, consisting of a lever, F, fulcrumed to a stand, G, which may be screwed to the inclined chute B, as shown, one end of this lever F being pivoted at f to a projecting end of the bar d, and the opposite 50 end, f', is held in contact with the drive-wheel H by means of the spring G', which may be secured to the chute B, as shown in Figs. 2 and

4. This drive-wheel H is provided with projections h on one side, which may be beveled, as shown best in Fig. 2, and the end f' of the lever F in riding over these ridges or projections h, which should be located at regular intervals around the wheel H, causes the screen D to shake laterally and allow the berries to escape through the horizontal slot or opening 60 d', formed in one end for this purpose, the said screen D being hung slightly inclining in order to facilitate the discharge of the berries, the lowest end being that in which is formed the said slot d'. The shaft I, upon which is 65 mounted the drive-wheel H, is supported in suitable bearings secured to the chute B, and carries at its opposite end a small pulley, J, connected by the belt K with a pulley, L, mounted upon the shaft M, which is hung in 70 bearings m, carrying between said bearings the cylinder N, having at regular intervals upon its periphery transverse slats or floats n. This cylinder N is designed to rotate in the direction indicated by the arrow in Fig. 1. 75

The chute B may be provided with a screen-bottom, B', for the entire distance from said cylinder to the lower end thereof; or said screen-bottom B' may extend only from the cross-beam b' to the beam b², and a narrow space, 80 B³, may be left between the said cross-beam b' and the remainder of the bottom of said chute, which may be solid and without openings or perforations of any kind. This construction I consider preferable. 85

The screen-bottom B' may be composed of rods running longitudinally and fastened in some convenient and firm manner to the cross-beams b' b²; or a cast grate may span the distance between the two beams with good results. The bottom D' in the vibratory screen D is also composed of rods similar to the rods used for the bottom B' of the chute B; or said bottom D' may be composed of a cast grate, as described above, for use in said chute B. 95

The rotation of the drive-wheel H by reason of the belt-pulleys J L and belt K revolves the cylinder N in the direction indicated by the arrow in Fig. 1, and the screen D, vibrated in the manner previously described, discharges 100 the berries upon said cylinder N, the imperfect berries and dirt, stems, &c., being carried over to the rear by the floats or slats n and dropped, while the perfect berries bound off

of the said cylinder and fall upon the screen-bottom B' of the chute B.

During the above-described operation any stems and dirt or imperfect berries which escape, being carried or deposited to the rear by the cylinder N, pass through the screen-bottom B'; or, in any event, the refuse matter will, if it has escaped the cylinder N and screen B', drop through the transverse opening or slot B³ before the final discharge or passage of the perfect berries through the mouth of the chute B.

Having described my improvements, what I claim as my invention is—

- 15 1. The combination of a receiving-hopper, a vibratory screen located directly under the same, a rotary cylinder, and radial transverse floats or slats arranged at regular intervals thereon, an inclined chute having a screen or grated bottom adapted to receive the perfect berries from said cylinder, and suitable operating mechanism for the vibratory screen and rotary cylinder, substantially as and for the purpose set forth.

2. The combination of a receiving-hopper, 25 an inclined vibratory screen located directly under the same, a rotary cylinder, and radial floats or slats secured at regular intervals thereon, an inclined chute adapted to receive the perfect berries from said cylinder, having a screen forming a portion of the bottom thereof, and provided at the lower end of said screen with a transverse opening or slot, and operating mechanism, substantially as and for the purpose specified. 30

3. In a machine for separating cranberries, the combination, with a hopper, a horizontally-vibratory screen, and an inclined chute, of a rotary cylinder located between said screen and chute revolving toward the former, and having radial slats for carrying away the imperfect berries and other refuse, substantially as described. 35

HALE CHADWICK.
